[57] **CLAIM**

The ornamental design for a handpiece housing for ultrasonic therapy, as shown and described.

DESCRIPTION

FIG. 1 is a side perspective view of a handpiece housing for ultrasonic therapy, showing our new design;

FIG. 2 is a left side elevational view of the handpiece housing of FIG. 1;

FIG. 3 is a top view of the handpiece housing shown in FIG. 1;

FIG. 4 is a bottom view of the handpiece housing of FIG. 1;

FIG. 5 is a rear end view of the handpiece housing of FIG.

1;

FIG. 6 is a front end view of the handpiece housing of FIG.

1.

The right side elevation view is the mirror image of the left side elevation view.

The broken line showing of the switch, indicator light, cable connector and portion of the cable in FIGS. 1–6 is for illustrative purposes only and forms no part of the claimed design.
